UNITED STATES PATENT OFFICE.

LOUIS J. STREUN, OF BLOOMFIELD, NEW JERSEY, ASSIGNOR TO BEAVER MANUFACTURING CO., INC.

DESIGN FOR AN ELECTRIC-APPLIANCE PLUG.

Application filed August 25, 1928. Serial No. 27,962. Term of patent 7 years.

To all whom it may concern:

Be it known that I, LOUIS J. STREUN, a citizen of the United States, residing at 207 North Sixteenth Street, Bloomfield, in the county of Essex and State of New Jersey, have invented a new, original, and ornamental Design for an Electric-Appliance Plug, of which the following is a specification, reference being had to the accompanying drawing, forming a part thereof.

Figure 1 is a plan view of an electric appliance plug.

Figure 2 is an elevation of same.

Figure 3 is an enlarged sectional elevation view taken on line 3—3 Figure 1.

Figure 4 is a perspective view of the electric appliance plug.

I claim:

The ornamental design for an electric appliance plug, as shown.

Signed at Newark, county of Essex, State of New Jersey, this 24th day of August, 1928.

LOUIS J. STREUN.
